Primary Examiner — Susan Bennett Hattan(74) *Attorney, Agent, or Firm* — James F. McBride; Leonard W. Lewis; Steven W. Miller**CLAIM**

The ornamental design for a cap, as shown and described.

DESCRIPTION

FIG. 1 is a perspective view of a cap;
 FIG. 2 is a front view thereof; and
 FIG. 3 is a top view thereof; and,
 FIG. 4 is a bottom view thereof.

The broken lines in the drawings depict environmental subject matter only and form no part of the claimed design.
